(57) **CLAIM**

The ornamental design for an edge toolbox bottom guard, as shown and described.

DESCRIPTION

FIG. 1 is an upper right, front perspective view of a edge toolbox bottom guard showing my new design.

FIG. 2 is a bottom left perspective view of the edge toolbox bottom guard of FIG. 1.

FIG. 3 is a front elevation view of the edge toolbox bottom guard of FIG. 1.

FIG. 4 is an end view of the edge toolbox bottom guard of FIG. 1. The end view of the other end is the same.

FIG. 5 is a rear elevation view of the edge toolbox bottom guard of FIG. 1.

FIG. 6 is a top plan view of the edge toolbox bottom guard of FIG. 1; and,

FIG. 7 is a bottom plan view of the edge toolbox bottom guard of FIG. 1.

The edge toolbox bottom guard is shown with a symbolic break in its length. The appearance of any portion of the article between the break lines forms no part of the claimed design.
